DOOR CONSTRUCTION

Clyde W. Kelly, Detroit, Mich., assignor to Detroit Steel Products Company, Detroit, Mich., a corporation of Michigan

Application August 19, 1929, Serial No. 386,959

10 Claims. (Cl. 20—19)

The invention relates to door constructions and refers more particularly to baffle constructions for doors.

One of the objects of the invention is to provide a baffle between a door and a guide therefor throughout substantially the length of the door. Another object is to so construct the baffle that the door may be moved longitudinally of a curved guide. A further object is to provide a door with anti-friction means for engaging the guide. With these as well as other objects in view, the invention resides in the novel features of construction and combinations and arrangements of parts as more fully hereinafter set forth.

15 In the drawings:—

Figure 1 is a plan view of a door and guide construction embodying my invention;

Figure 2 is an enlarged plan view of a portion thereof with the guide in section;

20 Figure 3 is a side elevation thereof;

Figure 4 is a cross section on the line 4—4 of Figure 2;

Figures 5 and 6 are views similar to Figures 2 and 3, respectively, showing a modification;

25 Figure 7 is a cross section on the line 7—7 of Figure 5.

The invention is particularly applicable to doors movable longitudinally of curved guides, such as doors for airplane hangars, one of which is shown 30 in the present instance.

1 is the door which may be supported by suitable means, such as wheels, and 2 is the guide which is in the nature of an angle iron having a depending flange terminating above the door. 35 This guide has the straight and curved portions 3 and 4 respectively, along which the door is movable.

For closing the space between the door 1 and the straight guide portion 3 and forming an effective weather seal therebetween, the door has secured thereto a baffle formed of a section overlapping the depending guide flange at its inner side and sections overlapping the depending guide flange at its outer side and extending from opposite the ends of the first section to the ends of the door. These sections are so arranged that their adjacent ends overlap, but sufficient clearance is provided therebetween to permit the door to move along the 50 curved guide portion 4. In detail, the section overlapping the inner side of the depending guide flange comprises the roll carriers 5 secured to the upper portion of the door near its ends and extending upwardly therefrom and the plate 6 extending between the roll carriers 5 and prefer-

ably in the nature of an angle iron having one flange secured to the upper edge of the door by the screws 7 and the other flange extending upwardly therefrom. Rolls 8 having vertical axes are mounted upon the roll carriers 5 to engage 60 the inner side of the depending guide flange. The sections overlapping the outer side of the depending guide flange are alike and each comprises the roll carrier 9 secured to the upper portion of the door adjacent a roll carrier 5, but at the opposite side of the door and extending upwardly thereabove, and the plate 10 extending from the roll carrier 9 to the adjacent end of the door. This plate 10 is in the nature of an angle iron and has one flange secured to the upper edge of the door 65 by the screws 11 and the other flange extending upwardly therefrom. The roll 12 having a vertical axis is mounted in the roll carrier 9 in position to engage the outer side of the depending guide flange. The adjacent roll carriers 5 and 9 overlap, but are so positioned that their respective rolls 8 and 12 provide for the necessary angular movement of the door to the depending guide flange, while the door is moving along the curved portion 4 of the guide.

70 The roll carriers 5 and 9 are preferably identical, but are reversed end for end when applied to the opposite sides of the door. These roll carriers are secured to the door by the bolts 13 and the nuts 14 threaded upon these bolts, one of the 75 bolts extending through both of the adjacent roll carriers and serving in securing the same to the door. Each roll carrier also preferably has a flange portion extending over the upper edge of the door and secured thereto by the screws 15.

80 In the modification shown in Figures 5, 6 and 7, a roll carrier 16 is pivotally mounted at the outer edge of the door near each end. Each of these roll carriers is set into the recess 17 in the upper edge of the door and has the pin 18 extending vertically and journaled in the supporting 85 block 19 secured in the upper portion of the door. The portion of the roll carrier extending upwardly above the door is formed in two segments 20 which are spaced apart to receive therebetween the depending guide flange and the edges of these 90 segments are preferably provided with the parallel flanges 21. 22 is a plate secured to the upper edge of the door and extending between the roll carriers 16 and overlapping the flanges 100 21 of these roll carriers and the depending guide flange at its inner side. This plate may be formed and secured to the door in the same manner as the plate 6. 23 is a plate secured to the upper edge of the door and extending from each roll 105 21.

55 110

carrier 16 to the end of the door, this plate overlapping a flange 21 of the roll carrier and the depending guide flange at its outer side. Each of these plates 23 may be formed and secured to the door in the same manner as each of the plates 10. Rolls 24 having vertical pivots are mounted in the segments 20 of each roll carrier 16 to engage opposite sides of the depending guide flange.

From the above description it will be readily seen that I have provided a construction of baffle between a door and an adjacent guide therefor when the door is in closed position which extends throughout the length of the door and which provides for movement of the door along a curved guide. It will also be seen that the construction is such that anti-friction bearings for engaging the guide may be used to facilitate movement of the door from its closed to its open positions or vice versa.

20. What I claim as my invention is:

1. The combination with a guide having straight and curved portions and a door movable longitudinally of said guide, of a baffle extending throughout substantially the length of said door and comprising a section overlapping said guide and located at the inner side thereof, and sections overlapping said guide and located at the outer side thereof and extending beyond the ends of said first mentioned section.

30. 2. The combination with a guide having straight and curved portions and a door movable longitudinally of said guide, of a baffle extending throughout substantially the length of said door and comprising a section overlapping said guide and located at the inner side thereof, and sections overlapping said guide and located at the outer side thereof and extending beyond the ends of said first mentioned section, and anti-friction means at the adjacent ends of said sections and engaging opposite sides of said guide.

35. 3. The combination with a guide having straight and curved portions and a door movable longitudinally of said guide, of a baffle extending throughout substantially the length of said door and comprising a section overlapping said guide and located at the inner side thereof, and sections overlapping said guide and located at the outer side thereof and extending beyond the ends of said first mentioned section, said sections comprising plates and roll carriers secured to said door.

45. 4. The combination with a guide having straight and curved portions and a door movable longitudinally of said guide, of a baffle extending throughout substantially the length of said door and comprising roll carriers secured to said door near the ends thereof, a plate secured to said door and extending between said carriers at one side of said guide, and plates at the opposite side 55 of said guide secured to said door and extending from said carriers to adjacent the ends of said door.

50. 5. The combination with a guide and a door movable longitudinally of said guide and spaced therefrom, roll carriers secured to said door and

overlapping said guide at one side thereof, a plate secured to said door and extending between said roll carriers and overlapping said guide, roll carriers secured to said door adjacent to said first mentioned roll carriers and overlapping the opposite side of said guide, and plates secured to said door and overlapping said guide and extending from said last mentioned roll carriers to adjacent the ends of said door.

55. 6. The combination with a guide and a door movable longitudinally of said guide and spaced therefrom, of roll carriers pivotally carried by said door near the ends thereof and overlapping said guide at opposite sides thereof, a plate secured to said door and extending between said roll carriers and overlapping one side of said guide, and plates secured to said door and overlapping the opposite side of said guide and extending from said roll carriers to adjacent the ends of said door.

90. 7. The combination with a guide having straight and curved longitudinally extending portions connecting into each other at their ends and a door movable longitudinally of said straight and curved portions of a baffle upon and extending throughout substantially the length of said door and comprising a section overlapping said guide and terminating short of the ends of said door, and separate sections overlapping said guide and extending from points adjacent the ends of said door.

105. 8. The combination with a guide having straight and curved longitudinally extending portions connecting into each other at their ends and a door movable longitudinally of said straight and curved portions, of roll carriers secured to said door near the ends thereof, a plate carried by said door and extending between said carriers and overlapping said guide, and plates carried by said door and extending from said carriers to the ends of said door in overlapping relation with said guide.

110. 9. The combination with a guide and a door movable longitudinally of said guide and spaced therefrom, of roll carriers pivotally carried by said door near the ends thereof, a baffle member extending between said roll carriers and overlapping one side of said guide, and baffle members overlapping the opposite side of said guide and extending from said roll carriers to adjacent the ends of said door.

115. 10. In a closure mounting, the combination with a movable closure member, of a depending curved track for directing it on its movement, spaced sets of upstanding guide elements carried by the top of the door, adjacent to but removed from its upper corners, said guide elements movably embracing the track, an upstanding weather shield between the sets and overlapping the track at one side of the same, and weather shields at the ends of the door beyond the guide elements overlapping the side of the track opposite from that overlapped by the first shield.
